UNITED STATES PATENT OFFICE.

PHILIP D. LAIBLE, OF NEWARK, NEW JERSEY.

STEAMING-TRAY FOR BOTTLED BEVERAGES.

SPECIFICATION forming part of Letters Patent No. 661,804, dated November 13, 1900.

Application filed May 25, 1899. Serial No. 718,161. (No model.)

To all whom it may concern:

Be it known that I, PHILIP D. LAIBLE, a citizen of the United States, residing at Newark, in the county of Essex and State of New Jersey, have invented certain new and useful Improvements in Steaming-Trays for Bottled Beverages; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

The objects of this invention are to provide in a box or tray for containing bottled beverages a detachable bottom which can be disconnected from the walls or frame of the box or tray and left with the bottles thereon in any desired place, the other part of the box being carried away to be connected to another bottom; to thus render it unnecessary to leave an entire box with the bottles delivered, but only a portion of the box; to thus enable a smaller number of boxes to be used, and to thereby lessen the expense incident to handling bottled beverages; to enable an entire tray full of bottles to be steamed as one bottle without removal from the tray; to thus decrease the labor required, and to secure other advantages and results, some of which may be hereinafter referred to in connection with the description of the working parts.

The invention consists in the improved steaming-tray for bottled beverages and in the arrangements and combinations of parts of the same, all substantially as will be hereinafter set forth, and finally embraced in the clauses of the claim.

Referring to the accompanying drawings, in which like characters of reference indicate corresponding parts in each of the several views, Figure 1 is a side elevation of a steaming-tray of my improved construction, and Fig. 2 is a plan of the same. Fig. 3 is a sectional view on line α , Fig. 2, with the bottles and steaming-top removed. Fig. 4 is a perspective view of a certain removable bottom upon which the bottles stand in the tray. Fig. 5 is a side view of a portion of the steaming-top on an enlarged scale, and Fig. 6 is a plan of the same. Fig. 7 is a central vertical

section of a single cap of the steaming-top, and Fig. 8 is a similar section of an adjustable plunger adapted to work in said cap. Fig. 9 is an enlarged detail view of a portion of the end of the body-frame of the tray, and Fig. 10 is an edge view of the same. Fig. 11 is a side view showing my construction as applied to a beer-box or the like. Fig. 12 is a side view of a beer-box, showing a modification of construction; and Fig. 13 is a section of the same on line α' , Fig. 12.

In said drawings, a indicates the body-frame of a steaming-tray of my improved construction, and b indicates the detachable bottom. Said body-frame is preferably of rectangular shape and of the usual size adapted to contain two dozen bottles and is formed with opposite vertical sides a' a' and ends a^2 a^2 , which may be of either wood or metal, but preferably the latter, in which case said walls are of open-work construction, as shown, to secure greater lightness and economy of material. The body-frame a is open at the top and bottom, the four sides lying in upright planes, without projections to interfere with the upward movement of said frame away from the inclosed bottles. At the opposite ends a^2 a^2 are large centrally-disposed openings d d , which extend nearly to the top edge, so as to afford hand-holes or means for lifting the frame, and nearly to the bottom to provide space for certain locking devices hereinafter described. The handle portions of the frame above the openings d d may be suitably thickened or rounded, as at d' , so as to be easy to the hand. The ends of the body-frame are further recessed or notched upward from the bottom edge, as at e^3 , to admit certain wire arms or staples e on the removable bottom and allow the lower edges of the frame a to rest upon the floor of the removable bottom, and the locking devices above referred to are supported upon the outsides of the said ends.

The removable bottom b is preferably formed of sheet metal and has its edges bent or turned upward to form a vertical flange f' , extending around the floor f . The lower portion of the frame a fits within this flange f' when the parts are connected, the frame resting upon the floor f and the flange f' extending upward at the outer sides of the frame to

prevent any lateral movement of the floor with relation to the frame. The floor *f* is perforated, as at *g*, to drain all liquid out of the removable bottom, and the flange *f'* is 5 preferably extended upward at the middle of each end of the removable bottom, as at *h*, and provided with hand-openings *h'*, affording means for handling said removable bottom independent of the body-frame. Obviously any other suitable form of handle may 10 be employed, if desired.

At each end of the removable bottom *b*, and preferably at two points equidistant from the longitudinal central line, are arranged the 15 arms or staples *e*, before mentioned, each of which preferably comprises a piece of wire bent at right angles and having one arm, as *e'*, disposed parallel to the floor, with its end passing through the flange *f'* and suitably 20 riveted or soldered in place, the other arm *e''* being perpendicularly secured to the floor of the removable bottom in a similar manner.

When the body-frame *a* is applied to the bottom *b*, which is done by merely setting said 25 frame down upon the removable bottom, the walls of the frame fit within the flange *f'* of the removable bottom, their lower edges resting on the floor *f* of the bottom, and the upwardly-projecting staples or arms *e* lie in the recesses 30 *e³* in the lower edge of the frame. To engage said staples *e*, and thus connect the frame and removable bottom, I have provided the locking devices shown more particularly in Figs. 3, 9, and 10. The essential part of each locking 35 device consists of two hooked levers *i i'*, pivoted upon pins *i'*, so as to lie flat against the outer surface of the end of the removable bottom and work in a vertical plane between the end of the frame *a* and the flange *f'* of 40 the removable bottom *b* when the two said parts are united, sufficient space being provided therebetween for the purpose. Each of said levers *i* has a downwardly-extending arm *j* and a horizontal arm *k* and is pivoted 45 at the joining of said arms. The pivotal pin *i'* is arranged on the frame *a* slightly above and outwardly from the recess *e³* in the lower margin of the frame, and thus by raising or lowering the horizontal arm *k* the downwardly-extending arm *j* is caused to move in 50 front of said recess *e³* or to one side of it. The downwardly-extending arm *j* is provided at its inner edge next to the recess *e³* with a projection *j'*, forming a hook, and this projection *j'* is placed at such a height on the arm *j* that when the staple *e* on the removable bottom lies in the upper part of the recess *e³* and the arm *j* is moved in front of said recess the said projection underlies the 55 staple *e* and receives it in the hook-like recess formed at its upper side. It will be obvious that under this condition of things the frame and removable bottom are firmly connected by the four hooks arranged two at 60 each end, and the whole may be used as a complete tray. To enable a more ready connection to be made in case the hooked arm *j*

should be lying in front of the recess *e³* when it was desired to enter the staple *e* into said recess, I have beveled the lower end of the 70 arm *j* from the point of the projection *j'* downwardly to the outer edge of the arm, so that the staple will force the hooked arm *j* out of its way as the frame and bottom come together.

For the convenient operating of the hooked levers *i* a vertical plunger *m* is centrally disposed at the end of the frame *a*, said plunger carrying at the lower end a cross-head *n*, pivotally connected at its opposite ends to the 80 adjacent ends of the opposite levers *i i'*. At the top of the plunger is a finger-piece or pressure-piece *o*, conveniently disposed beneath the handles *d'* for lifting the frame *a*. The plunger *m* works in a perforation or bearing in a cross-bar *p*, suitably arranged on the frame *a* across the opening *d'*. A shoulder *m'*, or any other suitable form of stop below the cross-piece *p*, serves to limit upward movement of the plunger, and a sleeve *m²* or 85 equivalent device arranged on said plunger above the cross-piece *p* may prevent undue downward movement.

I prefer to place around the upper part of the plunger *m* a spiral spring *q*, adapted to 90 rest at its lower end upon the cross-piece *p* and press at its upper end against the finger-piece *o*, said spring thus normally serving to hold the levers *i* in locking position. To connect the frame and bottom, then, it is only 95 necessary to set or press the frame down firmly upon the removable bottom and the locking together will be done automatically. To separate the parts, the plunger is forced 100 downward by means of the finger-pieces *o*. It will be evident that any other arrangement 105 of springs to effect automatic locking might be used.

At the corners of the frame *a* are provided 110 interior sockets or slideways *r*, adapted to receive vertical standards 2 of a steaming-top 3 to be placed over the bottles in the tray during the steaming operation, so as to prevent displacement of the corks in the bottles, as is usual. The horizontal portion of said 115 steaming-top comprises an open-work plate or grating consisting of cross-bars 4 and 5, extending lengthwise and crosswise of the top, respectively, and being integrally joined at the points of crossing. The said 120 cross-bars are so disposed in relation to one another that they cross directly above the bottles placed in the tray, and at the junctions of the cross-bars are perforations providing bearings for vertically-adjustable 125 caps 6. Each cap comprises a bolt 7, working in said bearing and having at the top a finger-piece 8 and at the bottom a disk 9, concave at its under side to engage the cork of the bottle. The bolt 7 is provided with a lug 10, which works in a spiral groove 11 in the walls of the perforation, enabling the cap to be moved up or down with a screw motion. The cross-bars of the steaming-top prefer-

ably bend or curve upward, as at 12, to elevate their points of crossing or seats for the caps 6, and thus form a recess for the disks.

In operation the frame *a* and bottom *b* being connected the tray thus formed is filled with bottles. The steaming-top is then put on and lowered until it engages the tops of the bottles, where it is held by set-screws *s*, engaging the standards 2. The bottles, however, vary slightly in height, and it is necessary to screw down a greater or less number of the individual caps to engage the corks of the shorter bottles. The whole trayful of bottles is then steamed, and when this operation is completed the frame *a* is separated from the removable bottom, the bottles being left standing on said bottom, while the frame is carried off and connected to another bottom, which in order to facilitate matters may have been already filled with bottles.

It is obvious that instead of the steaming-top 3 being adjustable upon the frame *a*, as described, it might, if desired, be permanently secured to said frame, the removable bottom enabling bottles to be put in and taken out. It will also be evident from the above description of the use of my improved steaming-tray that my invention could be applied to a box for transporting bottled beverages, as shown in Fig. 11. In this case the steaming-top not being needed is dispensed with, and in order to enable the boxes to be piled one on top of another, the sides or walls *a'* extend upward above the top of the bottles. Interior partitions, either fixed, as at *t*, or removable, as at *t'*, may also be carried by the frame to prevent contact or breakage of the bottles. By this construction of a beer-box it is necessary in delivering to leave only the removable bottom with the bottles standing thereon and not the entire box. It is also obvious that a removable bottom might be more simply provided by having a flat plate 21, adapted to be slid into place through a slot at one side of the box, as shown in Figs. 12 and 13; but this construction would be less convenient and require more space for operation.

Other modifications and alterations might also be made without departing from the spirit or scope of the invention, and I do not wish to be limited by the positive descriptive terms

herein used except as the state of the art may require.

Having thus described the invention, what I claim as new is—

1. A receptacle for bottled beverages, consisting of a body portion having vertical walls and an open bottom permitting said body portion to be lifted up and away from the enclosed bottles, and a detachable bottom having staples or wires thereon, said body portion being provided with coöperating hooked levers and means for automatically operating the same, substantially as set forth. 65

2. The herein-described container for bottled beverages, comprising a detachable bottom provided with staples or hooks, a body portion open at the bottom, hooked levers pivoted on the body portion and adapted to engage said staples or hooks on the detachable bottom, and springs normally holding said levers in locking position, whereby the body portion and bottom are automatically united when pressed together, substantially 75 as set forth.

3. In a container for bottled beverages, the combination of a body-frame and a detachable bottom, hooked levers pivoted on the frame and adapted to engage the said bottom 80 and connect it to the frame, springs holding said levers in locking position, and finger-pieces for releasing said levers, substantially as set forth.

4. In a beer-box, the combination of a body-frame and a detachable bottom, said bottom being provided with staples or wires *e*, and the frame having pivoted thereon bent levers having hooked arms adapted to engage said staples or wires on the detachable bottom, a connecting-link for said levers and a vertical plunger fast at its lower end to said connecting-link a finger-piece at the top of said plunger and a spring normally holding said levers in locking engagement with the staples on the 95 detachable bottom, substantially as set forth.

In testimony that I claim the foregoing I have hereunto set my hand this 24th day of May, 1899.

PHILIP D. LAIBLE.
